UNITED STATES PATENT OFFICE.

EDWARD F. CALDWELL, OF NEW YORK, N. Y., ASSIGNOR TO THE PHOENIX
GLASS COMPANY, OF PITTSBURG, PENNSYLVANIA.

DESIGN FOR A GLOBE OR SHADE.

SPECIFICATION forming part of Design No. 26,642, dated February 16, 1897.

Application filed January 13, 1897. Serial No. 619,125. Term of patent 7 years.

To all whom it may concern:

Be it known that I, EDWARD F. CALDWELL, a citizen of the United States, residing at New York, in the county of New York and State of 5 New York, have invented a certain new and useful Design for a Globe or Shade; and I do hereby declare the following to be a full, clear, and exact description of the invention, such as will enable others skilled in the art to which 10 it appertains to make and use the same.

This invention has relation to designs for gas, electric-light, and lamp globes and shades; and it consists in the shape and configuration as hereinafter described, and as shown in the 15 accompanying drawings, wherein—

Figure 1 is a plan view, and Figs. 2 and 3 are side views, of a globe embodying the novel design.

The shape of the body A of the globe is in 20 vertical section approximately a spherical or spheroidal zone, the upper edge being in the plane of the widest portion of the sphere, from which the wall of the globe curves downwardly and inwardly to the narrowed terminal of the spherical portion indicated by the 25 dotted line x x. From this point the neck portion is produced on reversed curved lines,

which first converge and then flare, terminating at the lower edge of the neck. The neck portion is about one-fourth the full height of 30 the globe and the parts so proportioned as to render the design harmonious and pleasing. The body of the globe is divided into a series of flutes a, separated by rounded or bellied panels b, and both may be appropriately 35 etched. The upper edge of the globe is scalloped, each panel and flute being rounded, as shown. The highest portions of the flutes are slightly lower than the highest portions of the panels, the whole being the resultant of the 40 bisection of the globe at its upper edge by the revolution of a line describing a conical surface, the axis of which is coincident with the axis of the globe.

What I claim, and desire to secure by Letters Patent, is—

The design for globes or shades, substantially as shown and described.

In testimony whereof I have affixed my signature in presence of two witnesses.

EDWD. F. CALDWELL.
